INVENTOR,
William A. Caster,

Frank S. Appleman, BY
ATTORNEY

UNITED STATES PATENT OFFICE.

WILLIAM A. CASLER, OF LOUISVILLE, KENTUCKY.

STOKER.

1,263,035.

Specification of Letters Patent. Patented Apr. 16, 1918.

Application filed March 23, 1915. Serial No. 16,454.

To all whom it may concern:

Be it known that I, WILLIAM A. CASLER, a citizen of the United States of America, and resident of Louisville, in the county of 5 Jefferson and State of Kentucky, have invented certain new and useful Improvements in Stokers, of which the following is a specification.

This invention relates to stokers and has 10 for its object the provision of novel means for conveying fuel from storage bins to the hoppers of stokers, which latter are stationed at convenient positions with relation to the furnaces with which they are 15 adapted to coat for maintaining the fuel supply therein, and the provision of novel means for operating the conveyers which carry the fuel associated with novel means for automatically stopping the conveyer 20 actuator, said controlling means being regulated or moved by fuel delivered by the conveyer.

A still further object of this invention is to provide an arrangement of parts by 25 which the stoker hoppers are automatically supplied with fuel and in which the mechanism for delivering the fuel to the said hoppers is thrown out of action when the said hoppers are full, it being understood 30 that it is preferable to regulate the supply of fuel proportional to the consumption thereof, this invention being provided as a safeguard so that should the fuel supply to the hopper exceed the amount of fuel consumed, the conveyer driver or actuator 35 would be arrested.

It is furthermore an object of this invention to provide a stoker of the character noted in accessible position without occupying 40 portions of the space necessary for the boiler repairs and to so locate the means for moving the coal with reference to the stokers and boilers that inspection and repairs of either can be readily made.

In carrying out the invention, convenient 45 means are provided whereby the space occupied by the stoker and the means for delivering fuel thereto are below the lowest tubes of the boiler, thus permitting the 50 lighting of the boiler room by monitors or sky-lights, the said apparatus furthermore obviating the manipulation of swinging feed spouts and parts associated with such loose feed spouts, now in common use, the 55 said invention furthermore avoiding the coal dust usually caused when stoker hop-

pers are filled through such spouts as usually results when the coal drops into the bins.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a front elevation of a series of boilers with their stoker hoppers;

Fig. 2 illustrates a plan view of the boilers and stoker hoppers shown in Fig. 1 with the addition of a corresponding series 75 of boilers immediately opposite and facing the boilers shown in Fig. 1 and also the electric wiring system for controlling the conveyer motor;

Fig. 3 illustrates a right hand end elevation of the boiler shown in Fig. 2;

Fig. 4 illustrates a left hand end elevation of the boiler shown in Fig. 2;

Fig. 5 illustrates a sectional view on the line A—A of Figs. 2 and 3, on an enlarged 85 scale as compared with the scale of Fig. 1; and

Fig. 6 illustrates a sectional view on the line B—B of Fig. 5.

In these drawings, I identify the series 90 of boiler furnaces by the reference numeral 11 and I provide a series of stoker hoppers 12 positioned to deliver fuel to the furnaces, the said stoker hoppers being relatively low as compared with the furnaces, the object of 95 which has been stated.

A conveyer, preferably a screw conveyer, 13 extends along the boiler room and over the stoker hoppers. The chute or casing of the conveyer has openings 14 leading to the 100 stoker hoppers so that fuel carried by the conveyer and reaching the said openings falls into the hoppers. The openings may be closed by sliding gates 23. The conveyer casing is furthermore provided with 105 openings which communicate with the outlet spouts 15 through which fuel that has passed a hopper descends and in which it is confined.

The conveyer is supplied with fuel from 110 the storage bin 16 through the pipes or chutes 17 leading to the conveyer casing

and the conveyer is driven by a motor 18 through the coupling 19 which communicates the motion of the motor to the conveyer.

5 The motor employed in this system is preferably electrically driven and it is supplied with electricity through the conductors 20 and the speed of the motor is adjusted to meet requirements by a resistance 22 in the circuit. Each outlet or spout 15 has a switch 21 carried by a trap door 27 which is hinged to the outlet or spout 15, and the trap door furthermore carries one element of the switch by which the current through the conductors is controlled. 10 Each outlet or spout 15 is further provided with a cut off gate 26 so that any one or more of the outlets or spouts 15 can be closed according to the number of stokers 20 that are in operation. Should the end furnace be temporarily out of commission, one of the intermediate outlets would be opened, so that the fuel would not pass the point of the open outlet. Should one of the intermediate furnaces be out of commission, 15 the corresponding outlet or spout would be closed so that the fuel would be permitted to pass the intermediate outlet or spout, guarding the stoker hopper which is out of commission allowing the fuel to be conveyed to the more remote furnace.

In operation, the fuel which would be delivered to the outlet or spout would rise therein until its pressure against the door 27 would carry the said door outwardly and disengage the switch member carried thereby from the stationary switch member, thus breaking the circuit and arresting the motor. The dotted lines 29 of Fig. 6 illustrate the position of the fuel at the lower opening of the outlet or spout 15 and the said lower end is shown as terminating a distance above the floor line, which permits or establishes a clearance through which the fuel may be removed when it is desired to reestablish a circuit by closing the door of the outlet or spout.

As has been stated heretofore, it is the purpose of the inventor to have the mechanical stoker and parts associated therewith located below the space required for the repair of boilers, the lower line of which is indicated by the dotted line 31, of Fig. 3.

This patent is limited to claims covering 55 fuel conveyer control. For claims covering the relative location of conveyer, conveyer control means and boiler tubes, reference will be had to my copending application, Serial No. 203,939, filed Nov. 26, 1917.

60 I claim—

1. In combination with a series of stoker hoppers, a conveyer operating above the

stokers for delivering fuel thereto, means adjoining several stoker hoppers operated by fuel pressure for controlling the delivery of fuel to the stokers, and means for shifting the control of the delivery of fuel to any of the fuel pressure means adjoining the several stoker hoppers.

2. In combination with a series of stoker 70 hoppers a conveyer operating above the stokers for delivering fuel thereto, several stoker hoppers equipped with fuel pressure operated means for controlling the delivery of fuel to the stokers, means for shifting 75 the fuel delivery control to any of the several fuel pressure operated means.

3. In combination with a series of stoker hoppers a power driven conveyer operating above the stokers for delivering fuel thereto, 80 several stoker hoppers equipped with fuel pressure means for cutting off the power driving the conveyer, means for shifting the power control to any of the several fuel pressure operated power control means.

4. In combination with a series of stoker hoppers a variable feed conveyer operating above the stoker hoppers for delivering fuel thereto, several stoker hoppers equipped with fuel pressure operated means for controlling the conveyer, means for shifting 90 the conveyer control to any of the fuel pressure operated control means should the conveyer feed rate prove excessive.

5. In combination with a series of stoker 95 hoppers a conveyer operating above the stokers for delivering fuel thereto, several stoker hoppers equipped with fuel pressure operated means for controlling the delivery of fuel to the stokers, inoperative stokers in 100 the series, means for rendering inoperative the fuel delivery and control means of the inoperative stokers, means for shifting the control to any of the fuel pressure operated control means of the operative stoker 105 hoppers.

6. In combination with a series of stoker hoppers a conveyer operating above the stoker hoppers for delivering fuel thereto, means for operating the conveyer, an outlet spout adjacent each stoker, each outlet spout having a switch in circuit with the conveyer operating means and means for mounting the switch whereby back pressure of the fuel in the outlet spouts will break 110 the circuit for regulating the delivery of fuel to the outlet spouts.

In testimony whereof, I hereunto affix my signature in the presence of two witnesses.

WILLIAM A. CASLER.
